UNITED STATES PATENT OFFICE.

CHARLES A. CAMPBELL, OF WATERTOWN, NEW YORK, ASSIGNOR TO THE NEW YORK AIR BRAKE COMPANY, A CORPORATION OF NEW YORK.

LUBRICATOR.

Application filed June 6, 1923. Serial No. 643,691.

This invention relates to lubricators and particularly to lubricators intended for use on the cylinders of cross compound air pumps such as are used to charge the main reservoirs of railway air brake systems.

One feature of the invention is a mode of connecting a single lubricator so that it will feed oil to both the high and low pressure air cylinders. A further feature of the invention is the connection of the lubricator in such manner that a definitely greater quantity of oil is fed to the high pressure cylinder than to the low pressure cylinder, the rate of feed to both cylinders being under the control of the low pressure cylinder.

The lubricator proper is of the general type described and claimed in the patent to Bickel and Minnier, No. 1,446,412, February 20, 1923, but includes certain improvements which lead to a slightly changed cycle of operation and reduce the danger of clogging of the oil port. This feature of the invention is generally applicable to lubricators for compressors of the reciprocating type.

The preferred embodiment of the invention is illustrated in the accompanying drawings, in which:—

Fig. 1 is a fragmentary elevation showing the lubricator attached to a cross compound air pump.

Fig. 2 is a plan view of the lubricator and the supporting bracket formed integrally therewith.

Fig. 3 is a vertical axial section through the lubricator on the line 3—3 of Fig. 2.

Fig. 4 is a fragmentary section on the line 4—4 of Fig. 5, showing on an enlarged scale the arrangement of the oil and air ports for atomizing the oil.

Fig. 5 is a section on the line 5—5 of Fig. 4.

Referring first to Fig. 1, the high pressure steam cylinder is indicated at 6 and the low pressure air cylinder at 7. The pistons in these two cylinders are connected as usual by a piston rod 8. Similarly, the piston of the low pressure steam cylinder 9 is connected to the piston of the high pressure air cylinder 10 by means of piston rod 11.

The body of the lubricator is indicated in this view at 12 and is supported by two lugs or arms 13, shown in Fig. 2, which are bolted to the lower head of the steam cylinders. The shell 12 has a low pressure cylinder con-

nection 14 which is connected by a pipe 15 with a working space of the low pressure air cylinder 7, and a high pressure connection 16 which is connected by a pipe 17 with a working space of the high pressure air cylinder 10. Pipe connections to the working spaces of air cylinders are familiar in this art (see, for example, the Bickel et al. patent above referred to) and need not be further explained herein.

Turning now to Figs. 3, 4 and 5, the internal construction of the lubricator will be explained. The body 12 of the lubricator includes a central oil well or reservoir 18 and a surrounding jacket space 19. The jacket space 19 is in direct communication through a port 20 with the high pressure cylinder connection 16. The purpose of this is to heat the oil in the reservoir 18 by heat conveyed from the high pressure cylinder by air flowing to the jacket 19 on the compression stroke in this cylinder. Thus, some of the heat developed in the compressor is usefully applied to maintain the oil at a constant temperature regardless of atmospheric conditions.

The top of the reservoir 18 is provided with a threaded opening which is normally tightly closed by a dome-shaped cap 21, this construction being adopted to insure the presence of an air space above the oil in the reservoir 18, even if the reservoir 18 be filled to the very top. While it is not contemplated that the reservoir 18 will be filled above the shoulder 22, the port 23 is formed through the threaded portion of the dome 21 adjacent the sealing shoulder 24 so that, if the reservoir 18 is over-filled, the excess oil will escape through the port 23, thus permitting the cap 21 to be screwed tightly to its seat.

The existence of a closed air space above the oil in the reservoir 18 is essential to the operation of the device. The construction above described insures this condition and it removes any danger of forcing oil in excessive quantities to the compressor cylinders by the act of screwing the dome cap 21 to place.

The base of the shell 14 is formed with a horizontal port 25 which leads inwardly from the low pressure connection 14 and merges into a downwardly-extending port 26. The port 26 is connected at a lower level by a horizontal port 27 with an upwardly-

extending port 28. This leads past an upwardly-opening check valve 29 to the port 20 which, as heretofore described, is in direct communication with the high pressure cylinder connection 16. A screw plug 30 and a downwardly-extending stop pin 31 serve to limit the opening movement of the check valve 29 and, when removed, to permit the inspection and removal of the valve ball 29. The screw plug 30 is staked, as shown, to prevent unauthorized removal.

A threaded recess at the bottom of the reservoir 18 receives a shouldered and threaded plug 32 which has an axial port 33 which is directly above the vertical port 26 at its junction with the horizontal port 25. Fixedly mounted in, and making a tight joint with, the plug 32 is a vertical tube 34 whose bore communicates with the port 33. Near its upper end, the tube is formed with a peripheral groove or channel 35 and a small air port 36 which leads from the bore of the tube to this peripheral channel.

A cap member 37, fitting over and tightly closing the upper end of the tube 34, carries a depending tube 38 whose internal bore is slightly greater than the outside diameter of the tube 34. The tube 38 surrounds the tube 34 and thus provides a narrow annular port or passage 39 which leads from a point slightly above the bottom of the oil reservoir 18 to the annular groove or channel 35.

The cap member 37 is provided with a port 40 larger than and aligned with the port 36, the port 40 offering a direct communication from the annular channel 35 to the air space within the dome cap 21.

In the operation of the device, the check valve 29 prevents the high pressures which exist during the compression stroke in the high pressure air cylinder from entering the port 28. Consequently, these pressure surges merely serve to bring heat to the jacket 19.

On the compression stroke in the low pressure cylinder, however, the air under pressure arriving by the connection 14 passes through the ports 25 and 33 and the bore of the tube 34 to the port 36. The air discharging from the port 36 into the air space within the cap 21 draws oil up from the reservoir 18 through the annular ports 35 and 39 and discharges this oil in the form of a mist or spray through the port 40. Thus, at each compression stroke of the low pressure cylinder, the air space beneath the dome 21 is fed with a mixture of air and atomized oil.

The effect of this is to keep the air above the oil in the reservoir constantly saturated with oil vapor. When too much atomized oil is fed to this air, i. e., more than the air can support in the form of a finely distributed mist, the excess oil will condense on the walls of the dome 21 and drain back

into the reservoir so that, in such case, there is no tendency to feed oil in excessive quantities to the working spaces.

At the beginning of each suction stroke, there is a sharp drop of pressure in the low pressure cylinder, resulting in a sudden back-flow through the ports 40 and 36, tube 34 and ports 33 and 25 to the connection 14. This back-flow of the air from the space within the dome 21 results in the discharge of a substantial quantity of oil suspended in the air as a mist. Part of this oil follows the air current to the connection 14, but a larger part passes downward into the vertical port 26 because of the momentum of the oil and the sudden change of direction at the ports 33, 25 and 26.

At the end of each working stroke in the high pressure cylinder, i. e., just before the admission of air from the low pressure cylinder takes place, there is a sharp drop of pressure which results in a momentary flow through the ports 26, 27 and 28 past the check valve 29 to the high pressure cylinder connection 16 due to the compression of the air in the low pressure cylinder. This momentary flow carries the oil received by the port 26 to the high pressure cylinder.

The arrangement of the port 26 in a downward direction and in line with the port 33 serves as effective means for insuring the feed of more oil, and in fact approximately twice as much oil, to the high pressure cylinder than to the low pressure cylinder. It is well known that, because of the high temperatures existing in the high pressure cylinder, and for other reasons, the high pressure air cylinder should receive oil in approximately this proportion relatively to the low pressure cylinder.

It will be obvious to those skilled in air brake pump operation, and in the operation of other devices where the pump feeds a reservoir whose pressure is subject to wide fluctuations, that, while the terminal pressures of the low pressure cylinder are substantially constant, the discharge pressure of the high pressure cylinder varies widely. Consequently, if the rate of oil fed be dependent on pressure fluctuations in the high pressure cylinder, it will vary not only in proportion to the number of strokes per minute but also in a manner dependent on the fluctuation of reservoir pressure.

In the present invention, the rate of feed of oil is controlled solely by the low pressure cylinder and, consequently, the oil feed is proportional, or very nearly proportional, to the number of strokes per minute. Consequently, this invention offers a peculiarly desirable means for regulating the oil flow to both cylinders, and a simple and effective mode of proportioning the feed to the two cylinders, so that the high pressure cylinder receives the larger proportion of the oil.

As stated, the lubricator is generally applicable to compressors of the reciprocating type.

A single cylinder compressor may be fed with oil by connecting a working space of the cylinder in any desirable manner with the pipe connection 14 and by plugging pipe connection 16, so that the pressure surges in port 33 will cause the lubricator to feed oil in the manner described.

While the lubricator is of the general type described and claimed in the patent to Bickel and Minnier above mentioned, it has certain definite advantages thereover. The annular port 39 is less likely to become clogged than is any small drilled port used to obtain the same calibration. This feature, consequently, is one of practical importance in the operation of devices of this character, it being remembered that, in air brake service particularly, infallible operation is highly important.

The arrangement of the air port 36 also is different. Instead of forming the oil feeding port and the air port on opposite sides of the upstanding tube, so that atomizing action occurs on back-flow to the working space, these ports are so arranged that, on the compression stroke, the air port delivers an aspirating jet which draws up oil and sprays it into the closed air space of the lubricator. The oil atomized on the compression stroke is thereafter withdrawn from the lubricator and fed to the compressor on the ensuing suction stroke.

The difference in size between discharge ports 40 and 36, prevents the lift of the lubricating fluid during the discharge of the air from the space above the oil because air passes through port 40 much faster than it can escape through small port 36. This insures a pressure in annular groove 35 sufficient to prevent any lift of lubricating fluid by way of annular groove 39.

What is claimed is:—

1. The combination of a lubricator of the type in which oil is carried from the lubricator by pressure surges generated in a connected compressor working space; a plurality of compressor working spaces; tubular connections from said lubricator to said working spaces; and check valve means arranged to prevent pressure surges generated in any of said working spaces, except one, from reaching said lubricator through said tubular connections while permitting oil flow in the opposite direction in the intervals between surges.

2. The combination of a lubricator of the type which is caused to feed oil by fluid pressure surges conveyed to it from the working space of a compressor; two compressor working spaces; a pressure-conducting connection between said lubricator and one of said working spaces, arranged to transmit

pressure surges and to convey oil; a pressure-conducting connection between said lubricator and the other of said working spaces; and a check valve in the last named connection, arranged to close against flow from the working space to the lubricator and to open to permit flow from the lubricator to said working space.

3. The combination of a lubricator of the type in which oil is carried from the lubricator by pressure surges generated in a connected compressor working space; a plurality of compressor working spaces; tubular connections from said lubricator to said working spaces; and check valve means arranged to prevent pressure surges generated in any of said working spaces, except one, from reaching said lubricator through said tubular connections while permitting oil flow in the opposite direction in the intervals between surges, one of said pressure-conducting connections being branched off from another with a sharp change of direction, whereby unequal feed rates of oil through such two connections are had.

4. The combination of a compressor of the reciprocating type having a high pressure working space and a low pressure working space; a lubricator of the type in which fluid pressure surges atomize and convey oil from the lubricator; pressure-conducting connections between said lubricator and said two working spaces; and a check valve in one of said connections arranged to close against flow from the high pressure working space to the lubricator.

5. The combination of a compressor of the reciprocating type having a high pressure working space and a low pressure working space; a lubricator of the type in which fluid pressure surges atomize and convey oil from the lubricator; a jacket space surrounding said lubricator; pressure-conducting connections between the lubricator and said working spaces and between the jacket space and said high pressure working space; and a check valve arranged to prevent flow from the high pressure working space to the lubricator.

6. The combination of a compressor of the reciprocating type having a high pressure working space and a low pressure working space; a lubricator of the type in which fluid pressure surges atomize and convey oil from the lubricator; a branched pressure-conducting connection between the lubricator and said working spaces, that to the low pressure working space being formed with a pronounced change of direction at the point of branching, whereby oil is fed through the two branches at unequal rates; and a check valve arranged to prevent flow of pressure fluid from the high pressure working space to the lubricator.

7. The combination of a compressor of the

reciprocating type having a high pressure working space and a low pressure working space; a lubricator of the type in which fluid pressure surges atomize and convey oil from the lubricator; a pressure-conducting connection leading downward from the lubricator and thence to the high pressure working space; a second pressure-conducting connection leading in a generally horizontal direction from a point above the lower end of the downward extending portion of said first named connection to the low pressure working space; and a check valve arranged to prevent flow from the high pressure working space to the lubricator.

8. The combination of a closed shell adapted to contain oil and a confined body of air; a duct leading from a point below the level of oil to a point above the same, within said shell; a second duct arranged to discharge into the confined air within said shell in aspirative jet relation with the upper end of said first duct; and means for connecting said second duct with the working space of a reciprocative compressor.

9. The combination of a closed shell

adapted to contain oil and a confined body of air; a tubular member having a discharge port within said shell above the level of therein; a second tubular member surrounding the first and providing an intervening annular duct leading from a point near the bottom of said shell and terminating in a port alined with the port of the first tubular member; and means for connecting said first tubular member with the working space of a reciprocative compressor.

10. The combination of a closed shell adapted to contain oil and a confined body of air; a compressor of the reciprocating type; a pressure-conducting connection between a working space of said compressor and the air space in said shell; and aspirative jet atomizing means interposed in said connection operable by successive pressure surges entering said shell from said working space and serving to spray oil into said confined body of air.

In testimony whereof I have signed my name to this specification.

CHAS. A. CAMPBELL.

CERTIFICATE OF CORRECTION.

Patent No. 1,633,763.

Granted June 28, 1927, to

CHARLES A. CAMPBELL.

It is hereby certified that error appears in the printed specification of the above numbered patent requiring correction as follows: Page 4, line 29, claim 9, after the word "of" insert the word "oil"; and that the said Letters Patent should be read with this correction therein that the same may conform to the record of the case in the Patent Office.

Signed and sealed this 2nd day of August, A. D. 1927.

Seal.

M. J. Moore,
Acting Commissioner of Patents.
